W. M. WILLIAMS.
DRILL BIT PULLING DEVICE.

APPLICATION FILED MAY 8, 1917. RENEWED MAR. 25, 1919.

1,305,184.

Patented May 27, 1919.

UNITED STATES PATENT OFFICE.

WILLIAM M. WILLIAMS, OF TONOPAH, NEVADA, ASSIGNOR OF ONE-HALF TO BURNEY LANGSTON, OF RENO, NEVADA.

DRILL-BIT-PULLING DEVICE.

1,305,184.

Specification of Letters Patent. Patented May 27, 1919.

Application filed May 8, 1917, Serial No. 167,205. Renewed March 25, 1919. Serial No. 235,101.

To all whom it may concern:

Be it known that I, WILLIAM M. WILLIAMS, residing at Tonopah, in the county of Nye and State of Nevada, have invented 5 a new and Improved Drill-Bit-Pulling Device, of which the following is a specification.

This invention has special reference to an improved device or tool to be used in 10 connection with mines and particularly for pulling drills out of holes when they become stuck or fast by the cuttings in the holes and which usually works behind the drill during the operation of drilling.

15 Primarily, this invention has for its object to provide a simple and inexpensive device capable of being readily applied to the drill shank, and which can be quickly, expeditiously and effectively operated to produce the desired results.

With other objects in view that will hereinafter appear, my invention embodies the peculiar features of construction and novel arrangement of the parts hereinafter explained, specifically pointed out in the appended claims and illustrated in the accompanying drawing, in which:

Figure 1 is a perspective view of my invention, the same being shown as applied 30 for use.

Fig. 2 is a vertical section of the same applied for use, the dotted lines indicating the manner in which the lever is operated for effecting the desired pull on the drill 35 shank.

Fig. 3 is a horizontal section of the same taken substantially on the lines 3-3 on Fig. 2, the operative movement of the lever being indicated in dotted lines, and

40 Fig. 4 is a perspective view of the several parts that constitute my drill bit pulling device.

In the drawing, 1 designates a tubular body, the lower end of which is adapted for 45 being seated over the hole 2 in which the drill is held fast, and the said body 1, when operatively applied, fits over the exposed part of the drill shank, as is clearly shown in Fig. 1.

At diametrically opposite sides, the tubular body 1 has vertical slots 3-3, one of which opens through the upper or outer end of the body 1 and has its lowermost or inner end terminating with a supplemental slot 30 of reduced width, the purpose of which 50 will presently appear.

One edge of each of the slots 3 has ratchet teeth 31-32 and the said teeth are arranged on alternate edges of the slots, *i. e.*, the teeth 32, at one side, project relatively in a 60 direction opposite to the projection of the teeth 31 at the opposite side, the reason for which will be presently fully stated.

4 designates the drill bit and 40 the drill shank. 5 denotes a collar slidable over the 65 outer or free end of the drill shank to which it is fixedly clamped at the desired positions on the shank, by a wedge key 6.

7 designates, what I term, an operating lever and the same includes a central ring-like body portion 60 that fits around the shank when the parts are operatively applied and which, at diametrically opposite edges, has concaved seats 62 in which are received short oppositely disposed radial 75 journals 50-50 on the collar 5.

Lever 7 also includes a handle 70 and a pair of oppositely disposed bearing portions 63, each of which has a beveled face 64 to provide for a proper engagement or 80 seating of the opposite lever portions with the ratchet edges formed in their coincident slots 3-3.

By reason of the peculiar construction and novel arrangement of the parts so far 85 described and shown in the drawing, it is apparent that when a drill bit becomes stuck or fastened in the hole being drilled, all that is necessary is to slip one end 65 of the lever into the slot at one side of the body 90 1 after passing the ring portion of the lever over the outer or free end of the drill shank and then passing the handle end of the lever down through the upper or open end of the slot on the other side of the body until it 95 seats in the supplemental slot 30, as shown.

The collar 5 is then applied to the bit shank and is made fast thereto by the wedge

key and it is held with the trunnions 50 engaging the concaved seats in the ring-like portion of the lever.

When thus positioned, the tubular body with the attached parts is capable of turning back with the drill while pulling the same through the cuttings. To pull the drill back or loosen it from its clogged or jammed position in the hole, the free end of 10 the lever 7 is lifted to engage, say, the first notch at the bottom of the slot, at one side, after which, with the said free end acting as a fulcrum, the handle end of the lever is lifted up from its base or supplemental 15 slot and shifted laterally, as indicated by the dotted line *a* on the drawing, so as to seat in the first notch in the slot 3 at that side of the casing or body.

The free end of the lever is then lifted up 20 into the next notch at that end, while the handle is removed from its first notch and swung upwardly or outwardly, see the arrow *x*, and as the front end of the lever at this time acts as a fulcrum, the working of the 25 handle end of the lever tends to pull or lift the drill rod, it being understood that during the pull or lifting operations of the drill shank, the said shank and drill maintain their true position within the hole being 30 drilled and are practically under no lateral strain, since the rockable bearing of the clamping collar on the ring portion of the lever prevents it.

After the front end of the lever has been 35 again shifted to engage the next upper one of the adjacent notches, the handle end of the lever is again swung over to engage with its next adjacent upper notch and the several 40 operations of the lever, as explained, are repeated until the desired pull on the shank and bit is effected.

What I claim is:

1. A drill pulling device of the character described, comprising a frame adapted 45 for being seated over the hole being drilled, the said frame having a pair of diametrically opposite longitudinal guide slots, one of the edges of each slot having ratchet teeth, a collar for engaging the drill, means 50 for clamping the collar onto the said drill and a lever having a portion that forms a seat for the collar and bearing portions laterally shiftable in the guide slots of the frame and adapted for being shiftably 55 moved to engage their respective adjacent ratchet teeth of the frame.

2. A drill pulling device of the character described, comprising a frame adapted for 60 being seated over the hole being drilled, the said frame having a pair of diametrically opposite longitudinal guide slots, one of the edges of each slot having ratchet teeth, the teeth at one side being alternately arranged relatively to the teeth at the other side, a

collar for engaging the drill, means for 65 clamping the collar onto the said drill and a lever having a portion that forms a seat for the collar and having bearing portions laterally shiftable in the guide slots of the frame and adapted for being shiftably moved to 70 engage their respective adjacent ratchet teeth of the frame.

3. A device for pulling drill bits out of holes in which they become chocked, said device comprising a suitable frame adapted for 75 being seated around the drill bit shank and over the hole being drilled, said frame having diametrically opposite longitudinally extending guide slots, one of the slots opening through the outer end of the said frame, 80 each of the slots having ratchet teeth along one edge, a lever including an apertured body portion adapted for slipping over the drill shank, the said lever having a handle extension at one end and a front extension, 85 said handle portion and front extension being removably insertible through the longitudinal slots in the frame and having portions for engaging the ratchet teeth in the edges of their respective slots, a collar and 90 means for clamping the collar on the drill shank, said collar being adapted to seat on the body portion of the lever.

4. A device for pulling drill bits out of holes in which they become chocked, said 95 device comprising a suitable frame adapted for being seated around the drill bit shank and over the hole being drilled, said frame having diametrically opposite longitudinally extending guide slots, one of the slots 100 opening through the outer end of the said frame, each of the slots having ratchet teeth along one edge, a lever including an apertured body portion adapted for slipping over the drill shank, the said lever having a handle extension at one end and a front extension, 105 said handle portion and front extension being removably insertible through the longitudinal slots in the frame and having portions for engaging the ratchet teeth in the edges of their respective slots, a collar and 110 means for clamping the collar on the drill shank, said collar having a pair of oppositely projected radial trunnions and the body portion of the lever 115 having concaved seats for receiving the said trunnions.

5. As a new article, a drill shank pulling device which comprises a tubular member having a pair of diametrically opposite 120 longitudinal slots, one of the said slots opening through the upper end of the said member, each of the slots having one edge formed with ratchet teeth, the said tooth edges being alternately disposed, a lever that includes a ring portion adapted to fit over the drill shank and having a pair of oppositely extended concaved seats, the said lever also

including a front member adapted for extending through the slot at one side and co-acting with the teeth at the said side and a handle extension at the other end adapted for being slipped down through the open end of the slot at the other side of the tubular member and for coacting with the ratchet

teeth in the said slot, a collar and means for clamping the collar on the drill shank, said collar having radial trunnions for seating in 10 the concaved seats in the ring portion of the lever.

WILLIAM M. WILLIAMS.
